FASTENING DEVICE

Fritz Haase, Wohlen, Switzerland

Application August 16, 1937, Serial No. 159,424
In Switzerland September 26, 1936

7 Claims. (CL 24—207)

The present invention relates to improvements in fastening devices particularly for body garments without the use of sliders or intermediate pieces, the devices comprising a canal or channel 5 provided on one of the parts to be coupled or fastened together and an insertable rib or bead- ing provided on the other part.

Devices of this kind are known in which the canal is formed by strips of fabrics sewn to the garment part. Such strips are apt to be pulled asunder by a tension acting at right angles to the fastening device, such devices being therefore only suitable for round parts. Furthermore it is difficult to insert the portion mating 10 the canal and consisting of a rib-shaped strip of fabric, as the strips forming the canal are not sufficiently rigid so that the mating part slips easily out of the canal. To avoid this drawback it has been proposed to reinforce the fabric strips forming the canal and the mating bead-shaped part in order to obtain a stronger fastening. Such a reinforcement is not easily to be carried out in practice, furthermore the connection becomes very thick and bulky and can 15 only be bent in one direction.

In another arrangement buttons are inserted into a canal formed by strips of fabric. This arrangement has the above mentioned disadvantages as regards the strips of fabric and further the buttons tend to increase the bulkiness.

Other known devices in which the connection is obtained by means of sliders and intermediate pieces are not suitable for fastening parts of launderable clothing such as collars or cuffs to shirts as the fastening is too cumbersome and the means are too bulky.

With the device according to the present invention the above mentioned drawbacks are overcome as the canal comprises a stiffening portion 40 in the form of a wire insertion around which the fabric is placed. This stiffening portion effectively prevents the mating part from being pulled sideways out of the canal. The device may thus not only be used for round edged garments but 45 also for those which are flat when worn; it is flexible in any direction and may be fixed to the edges of the parts to be fastened to each other without causing an essential thickening at the fastening place. Further the device may be 50 manufactured in a simple and cheap manner and may be applied to launderable clothing as it can be washed and ironed.

By inclosing the stiffening portion by means of two layers of fabric cut diagonally this portion 55 may be rendered invisible from the outside.

The wire insertion may consist of a portion of non-corrosive wire which has portions bent according to the shape of the canal and connecting parts.

Further sleeves serving for reinforcing may be 5 provided at the ends of the fastening. The canal may also have interruptions.

If the fastening is used for shirt and collar connections, a covering layer may be provided on the collar to cover the connecting elements between 10 the shirt and collar.

In order to prevent the beading portion from being easily pulled out of the canal by a pull acting at right angles to the canal and to avoid the connecting means being comparatively bulky the 15 canal consisting of the wire insertion covered by the fabric may have flattened side walls the edges of which are bent inwardly at the open slit-shaped side of the canal. These edges render it difficult for the beading to be pulled out of the 20 canal by a pull acting at right angles to the fastening device, while the flattened side walls permit a small thickness of the fastening device so that the device may be used for connecting collars to shirts.

Preferably at one end of the canal an end sleeve forming a continuation of the wire support and bent to the same cross-section as the latter is provided. The end sleeve may have at 25 its inner end a bent elongation piece which extends along the outer side of the bottom of the supporting wire. This sleeve stiffens the ends of the canal without increasing the thickness of the fastening device.

The inner portion of the fabric covering of the canal may be sprayed with a putty that stands 30 washing at boiling temperature and the intermediate space between the wires of the support and the outer and inner portion of the covering fabric may be filled with flakes of wool. The spraying of the inner portion of the covering fabric permits a good gliding of the beading in the canal and the wool flakes hide the wire support from view.

Advantageously the string or cord forming the 35 core of the rib consists of braided viscose threads and is impregnated with a putty withstand- 40 ing boiling and a fabric covering is glued to the string or cord. This cord maintains its round shape during washing and ironing and when subjected to tension and compression without its flexibility being impaired. At the ends of the cord guiding pins may be provided which may be fixed to the 45 fabric and may be provided with a guide head ex- 50 tends beyond the fabric. These guide pins 55

enable an easy insertion of the beading into the canal.

Constructional examples of the device according to the invention are illustrated on the accompanying drawings, in which:

Fig. 1 shows in a plan view a collar provided with a fastening device according to the first exemplification,

Fig. 2 shows the upper edge of a shirt with which the collar is to be connected.

Fig. 3 is an enlarged sectional view of a collar and part of a shirt showing the fastening device connected.

Fig. 4 is a partial longitudinal section through the canal;

Fig. 5 is a horizontal section of Fig. 4;

Fig. 6 is a cross-section along line VI—VI in Fig. 5;

Fig. 7 is a cross-section along line VII—VII in Fig. 5;

Fig. 8 is a detail view of the wire support of the canal;

Fig. 9 shows a vertical longitudinal section along line IX—IX of Fig. 10 through one end of the canal of a second constructional example;

Fig. 10 is a cross-section along line X—X in Fig. 9;

Fig. 11 is a plan view of Fig. 9;

Fig. 12 shows an end sleeve in a perspective view;

Fig. 13 is an end view of a rib or beading, and

Fig. 14 is a side view of the rib or beading shown in Fig. 13.

In the constructional example illustrated in Figs. 1-8 1 denotes a collar provided at its edge to be connected with the shirt with a rib or beading 2, which, as is shown in Fig. 3, may consist of a core 2' and of a fabric covering 2'' enveloping the core. The core 2' consists preferably of tin-coated and braided copper strands and the fabric 2'' is sewn to the collar 1. At the upper edge of the shirt 3 to which the collar is to be fastened a canal of channel 4 is formed into which the rib or beading 2 of the collar 1 is to be inserted in order to fasten the collar to the shirt. A covering strip or apron 5 is provided on the collar 1 which covers the beading 2 and the canal 4 and renders these fastening elements between collar and shirt invisible from outside.

As may be seen in Figs. 4-8 the canal 4 is provided with a stiffening insertion in the shape of a wire support 4', a sleeve 4'' serving for strengthening purposes being pushed over each end portion of the wire device. A fabric 4''' is placed around the supporting wire 4' and the sleeves 4'', the inner portion of this fabric being sewn to the wire support 4' and the edges of this fabric projecting beyond the supporting wire and being sewn to the shirt 3. The supporting wire 4' has incomplete ring-shaped portions 4'1 adapted to the shape of the canal 4 and straight, longitudinally extending connecting portion 4'2 which are situated alternately on opposite sides of the canal so that the supporting wire 4' may be produced of a single piece of wire suitably bent and made of a non-corrosive material (Fig. 8).

The core 2' of the beading 2 may also be formed of a cord or string instead of a stranded copper wire, the string being impregnated by a material which is insoluble in water and is not affected by heat, so that it will always maintain its shape, that is, will not become soft nor flattened.

The string may also consist of rubber, whereby the rib is easier to be inserted into the canal and cannot be pulled sideways out of the latter. Such

a rubber string has the further advantage that it is not deformed by washing and ironing.

Sleeves 4'' may also be provided at intermediate parts and not only at the ends of the canal.

Further instead of one layer of fabric two layers 5 may be placed around the supporting wire of the canal, which are both cut diagonally so that the wires of the supporting wire may less easily be seen through the fabric. The inner layer of fabric consists suitably of flannel.

It is not necessary that the canal and the mating part extend over the whole length to be connected, the canal and the mating part or both may have interruptions or may consist of larger or smaller portions arranged at distances from each other.

The above described fastening device is also suitable for detachable connection of other parts of garments, for example for detachably fastening cuffs to shirt sleeves.

The canal illustrated in Figs. 9-11 is provided with a stiffening insertion in the shape of a supporting wire 6 which comprises ring-shaped portions 6' adapted to the shape of the canal and connecting parts 6'' which are situated alternately at opposite edges of the canal side opening, so that the supporting wire 6 may be produced by bending of a single piece of wire. The supporting wire 6 has flattened side walls having curved edges (Fig. 10) at the open side of the canal. At each end of the canal an end sleeve 7 is provided which has the same cross-section as the support 6 and forms a continuation of the latter. The end of the support 6 is fixed to the end sleeve 7. The lower part of the end sleeve 7 35 has an offset elongation 7' (Fig. 12) which extends along the outside of the lower side of the supporting wire 6.

The covering 8 of fabric is placed around the supporting wire 6 and the end sleeve 7. The inner portion of the covering 8 placed in the hollow space of the canal is impregnated previous to placing the outer portion with a putty which is not affected by boiling; thereupon flakes of wool 9 are pressed into the interstices between the loops of the supporting wire 6 so that the supporting wire 6 cannot be seen from the outside after the outer portion of the covering layer has been applied. The fabric of the covering layer 8 is diagonally cut whereby the wires are less visible and a finer fabric may be used. The two outer portions of the covering fabric 8 are sewn together along a seam 10 at the lower part and a straight cut strip 11 of fabric may be sewn in the seam for stiffening purposes. The parts of the fabric may also be glued together by an adhesive instead of being sewn together.

The core of the rib (Figs. 13 and 14) consists of a cord 12 of tightly tensioned viscose threads braided together and impregnated by means of a putty fast to boiling. Such a cord remains always round in cross-section, since washing and ironing as well as tension and compression do not affect it and its flexibility is maintained. At each end of the cord 12 a guide pin or tab 13 is clamped having a guide tab head 13' projecting beyond the fabric 14 placed around the cord 12 and the pin 13. The covering fabric 14 is fixed by means of an adhesive to the cord 12 and over the whole length of the latter. The guide pin 13 is provided with notched portions 13'' by means of which it is held in the fabric. Around the end of the covering fabric 14 end pieces 15 are placed and fixed thereto by an adhesive whereby the guide pin 13 is prevented from getting de-

tached and a stiffening of the beading is obtained.

By spraying a boiling-proof putty on the inner covering fabric 8 of the canal and by fixing the covering fabric 14 to the cord 12 a diminution of the friction when the beading is inserted into the canal is obtained and the insertion is facilitated. This facilitated inserting permits a reduction of the size of the canal.

10 I claim:

1. Mechanism for attaching edges of garments together along extended lines comprising; means forming an elongated continuous channel attached to one garment edge, said means comprising a reinforcing frame of flexible wire formed in loops, and longitudinally extending straight portions along the open edges of the channel between said loops; the loops of wire being generally semi-circular opposite the channel, and, adjacent the channel, extending inwardly directly toward the channel edges substantially perpendicularly thereto, an interior and exterior covering for said reinforcing frame, said covering being composed of fabric which is cut diagonally in order to better obscure the shape of the underlying frame, said covering being directly attached to said garment edge, the other garment edge having a beading substantially coextensive with the channel adapted to be drawn into the channel endwise, the beading being covered with fabric and being flexible, and the fabric cover of the beading being attached to said other garment edge.

2. Mechanism for attaching edges of garments together along extended lines comprising; means forming an elongated continuous channel attached to one garment edge, said means comprising a reinforcing frame of flexible wire formed in loops, and longitudinally extending straight portions along the open edges of the channel between said loops; the loops of wire being generally semi-circular opposite the channel, and, adjacent the channel, extending inwardly directly toward the channel edges substantially perpendicularly thereto, the loops of wire for forming said channel frame being spaced apart, the spaces between said loops being filled with wool, an interior and exterior fabric covering for said reinforcing frame, said covering being directly attached to said garment edge, the other garment edge having a beading substantially coextensive with the channel adapted to be drawn into the channel endwise, the beading being covered with fabric and being flexible, and the fabric cover of the beading being attached to said other garment edge.

3. Mechanism for attaching edges of garments together along extended lines comprising; means forming an elongated continuous channel attached to one garment edge, said means comprising a reinforcing frame of flexible wire formed in loops, and longitudinally extending straight portions along the open edges of the channel between said loops; the loops of wire being generally semi-circular opposite the channel, and, adjacent the channel, extending inwardly directly toward the channel edges substantially perpendicularly thereto, an interior and exterior fabric covering for said reinforcing frame, said covering being directly attached to said garment edge, the other garment edge having a beading substantially coextensive with the channel adapted to be drawn into the channel endwise, the beading being covered with fabric and being flexible, and the fabric cover of the beading being

attached to said other garment edge, the interior portion of the fabric frame covering within the channel being impregnated from the inside with boiling-proof putty to facilitate sliding of the beading in the channel.

4. Mechanism for attaching edges of garments together along extended lines comprising; means forming an elongated continuous channel attached to one garment edge, said means comprising a reinforcing frame of flexible wire formed in loops, and longitudinally extending straight portions along the open edges of the channel between said loops; the loops of wire being generally semi-circular opposite the channel, and, adjacent the channel, extending inwardly directly toward the channel edges substantially perpendicularly thereto, the sides of the loops of wire between the semi-circular portions and the portions extending inwardly toward the channel being flat so that the thickness of the attachment mechanism will be small, an interior and exterior fabric covering for said reinforcing frame, said covering being directly attached to said garment edge, the other garment edge having a beading substantially coextensive with the channel adapted to be drawn into the channel endwise, the beading being covered with fabric and being flexible, and the fabric cover of the beading being attached to said other garment edge.

5. Mechanism for attaching edges of garments together along extended lines comprising; means forming an elongated continuous channel attached to one garment edge, said means comprising a reinforcing frame of flexible wire formed in loops, and longitudinally extending straight portions along the open edges of the channel between said loops; the loops of wire being generally semi-circular opposite the channel, and, adjacent the channel, extending inwardly directly toward the channel edges substantially perpendicularly thereto, an interior and exterior fabric covering for said reinforcing frame, said covering being directly attached to said garment edge, the other garment edge having a beading substantially coextensive with the channel adapted to be drawn into the channel endwise, the beading being covered with fabric and being flexible, and the fabric cover of the beading being attached to said other garment edge, one end of the channel forming means being provided with a stiff metal sleeve of corresponding size and general cross-section as the wire frame of the channel for stiffening said end to facilitate insertion of the beading.

6. Mechanism for attaching edges of garments together along extended lines comprising; means forming an elongated continuous channel attached to one garment edge, said means comprising a reinforcing frame of flexible wire formed in loops, and longitudinally extending straight portions along the open edges of the channel between said loops; the loops of wire being generally semi-circular opposite the channel, and, adjacent the channel, extending inwardly directly toward the channel edges substantially perpendicularly thereto, an interior and exterior fabric covering for said reinforcing frame, said covering being directly attached to said garment edge, the other garment edge having a beading substantially coextensive with the channel adapted to be drawn into the channel endwise, the beading being covered with fabric and being flexible, and the fabric cover of the beading being attached to said other garment edge, one end of said beading having a longitudinally extending

metallic tab to facilitate insertion of the beading into the channel endwise.

7. Mechanism for attaching edges of garments together along extended lines comprising; means forming an elongated continuous channel attached to one garment edge, said means comprising a reinforcing frame of flexible wire formed in loops, and longitudinally extending straight portions along the open edges of the channel between said loops; the loops of wire being generally semi-circular opposite the channel, and, adjacent the channel, extending inwardly directly toward the channel edges substantially perpendicularly thereto, an interior and exterior fabric

covering for said reinforcing frame, said covering being directly attached to said garment edge, the other garment edge having a beading substantially coextensive with the channel adapted to be drawn into the channel endwise, the beading being covered with fabric and being flexible, and the fabric cover of the beading being attached to said other garment edge, and a fabric apron attached to one of the garments along a line approximately parallel with, and in the proximity 5 of the attachment and covering the attachment mechanism to hide it from view. 10

FRITZ HAASE.
